S. EMERSON, SR.
SIDEWALK SIGN FASTENER AND PROTECTOR, CENTRALLY OPERATED.
APPLICATION FILED MAR. 1, 1920.

1,356,056.

Patented Oct. 19, 1920.

Inventor:
Stephen Emerson, Sr.

UNITED STATES PATENT OFFICE.

STEPHEN EMERSON, SR., OF PHILADELPHIA, PENNSYLVANIA.

SIDEWALK-SIGN FASTENER AND PROTECTOR, CENTRALLY OPERATED.

1,356,056.

Specification of Letters Patent.

Patented Oct. 19, 1920.

Application filed March 1, 1920. Serial No. 362,422.

To all whom it may concern:

Be it known that I, STEPHEN EMERSON, Sr., citizen of the United States, residing at 2025 North Randolph street, Philadelphia, in the county of Philadelphia and State of Pennsylvania, have invented certain new and useful Improvements in Sidewalk-Sign Fasteners and Protectors, Centrally Operated, of which the following is a specification.

My invention relates to a sidewalk sign fastener and protector, centrally operated, and the object of my invention is to protect and securely fasten sidewalk signs by means of a construction operated by a lock lever, a spring and a rod having a hooked end, suspending from the lock lever through the center of a slot in the base construction, which hooked end rod is fastened to a ring, which is fastened to the ground, pavement, floor or any other supporting surface upon which the sign may stand, thus preventing theft or damage to sidewalk signs by being thrown, blown or kicked over.

A model of my invention is respectfully submitted.

In the accompanying drawing Figure 1 is a side elevation of my invention, Fig. 2 is a side view of the lever construction mounted on the frame, Fig. 3 is an end view of lever construction, Fig. 4 is a perspective view of the lever.

My invention of a sidewalk sign fastener and protector is centrally operated, consisting of a construction (A), with two elevated arms (B), having a slot (C) in the center of the base of said construction, and a screw eye (D) at the left end of the base. This construction is fastened to the top, at the center, of sign to the frame of one leaf of the folding sign, by means of three screws in the front of the base construction, allowing the other leaf of the folding sign to be free. The two leaves of the folding sign are hinged together at each end at the top. To this construction is attached a lock lever (E) by two pivot screws through the top of the two elevated arms. This lever has a slot at one end (F) which fits over the screw eye in the base when the lever is drawn down over it to draw the resilient connection taut.

A space (G) is cut through a portion of the center of the lever and a cotter pin (H) put from one end of the other, from which cotter pin suspends a rod (I), going

through the slot at the base of the construction, to which is attached a spring (K). From the lower end of this spring suspends another rod, having a hook at the end, which hooks into a connecting device fastened to the ground, pavement, floor or other supporting surface. The rod and the spring form a resilient connection between the lever at the top of the sign at one end, and a connecting device on the supporting surface at the other end.

When the hooked rod is hooked into the connecting device fastened in the ground, pavement, floor or any other supporting surface upon which the sign may stand, and the lock lever (E) is brought into position or drawn down over the screw eye (D) in the base construction, it stretches the spring and brings the rod into tension, forming a resilient connection between the lever at the top of the sign and the connecting device in the supporting surface, holding the legs of both leaves of the folding sign fast to the ground, pavement, floor or supporting surface, making the sidewalk sign steady, firm, and immovable, preventing theft, or damage to sidewalk signs by being thrown, blown, or kicked over. A padlock may be placed into the screw eye (D), and signs thus protected may remain out all night.

When the arm of the lock lever, which fits over the screw eye (D) is raised, the tension is loosened, and the hooked rod can be unhooked from the connecting device fastened to the ground, pavement, floor or any other supporting surface, and the sign freed, allowing the leaves of the sign to be folded together and moved.

I claim as my invention:

1. The combination in a sidewalk sign fastener and protector, centrally operated, consisting of a construction, fastened to the top center of one leaf of folding sign, said construction having a lock lever pivoted to two elevated arms, from the end of one arm of the lock lever extending a rod, through a slot in the base of said construction, to which is attached a spring and another rod having a hooked end, hooking into a connecting device fastened to the supporting surface forming a resilient connection between top center of sign and supporting surface.

2. In a sign fastener and protector, in combination, a resilient connection between

the supporting surface and the top of the sign, a lever mounted on top of the sign to draw the resilient connection taut, and means to hold the lever in operative position.

3. In a sign fastener, the combination of a frame fastened to the top center of one leaf of the folding sign, a locking lever, pivotally mounted in said frame, a resilient connection fastened at one end to a connecting device mounted on the supporting

surface and at the other end to an arm of the pivoted lever, means on the frame to retain the other arm of the lever in a lowered position thereby raising the first named arm 15 and drawing the resilient means taut.

In testimony whereof I have affixed my signature.

STEPHEN EMERSON, Sr.
